UNITED STATES PATENT OFFICE.

THOMAS VAUGHN AND ROBERT A. CONVERY, OF TRENTON, NEW JERSEY.

DESIGN FOR A LETTER-FILE.

SPECIFICATION forming part of Design No. 19,902, dated June 10, 1890.

Application filed March 13, 1890. Serial No. 343,782. Term of patent 3½ years.

To all whom it may concern:

Be it known that we, THOMAS VAUGHN and ROBERT A. CONVERY, citizens of the United States, residing at Trenton, in the county of Mercer and State of New Jersey, have invented a new and original Design for Letter-Files, of which the following is a specification.

The invention relates to a new and original design for letter-files.

The object of the present invention is to provide an ornamental and attractive clasp for letter-files.

In the drawings, the figure represents a perspective view of a letter-file showing our new design.

The leading feature of our design is the clasp having the small loop at the top and the large loop forming the body.

Referring to the accompanying drawing, 1 designates a clasp having similarly-curved sides 2, that are provided near the top with short curves that form the small loop 3, and below the short curve with longer curves 25 that form the large loop 4 at the body of the

clasp, and the curved sides 2 have eyes 5 arranged at their ends. The clasp is provided near the eyes 5 with coils 6.

7 designates a curved plate that is provided with perforations, and is arranged at 30 the ends of the sides 2, and has its perforations arranged opposite the eyes 5.

What we claim is—

A design for letter-files herein shown and described, the same consisting of the clasp 35 having its sides 2 provided with the long and short curves, forming the small loop 3 and the large loop 4, and having its ends provided with eyes and having the coils arranged a short distance from the eyes, and the curved 40 plate, as set forth.

In testimony that we claim the foregoing as our own we have hereto affixed our signatures in presence of two witnesses.

THOMAS VAUGHN.
ROBERT A. CONVERY.
